(57) **CLAIM**

The ornamental design for a round bollard LED light fixture, substantially as shown and described.

DESCRIPTION

FIG. 1 is a bottom perspective view of an embodiment of the new design;

FIG. 2 is a front side view of the embodiment;

FIG. 3 is a top view of the embodiment;

FIG. 4 is a bottom view of the embodiment; and,

FIG. 5 is a cross sectional view of a top portion of the embodiment taken along line 5-5 of FIG. 2.

The design consists of the features of shape, ornament and configuration of the article shown in the drawings. The broken lines shown in the drawings are for the purposes of illustrating portions of the article that form no part of the claimed design. The right, left, and back side views are the same as the front side view and are therefore omitted. The cross-sectional view illustrated is FIG. 5 is at an enlarged scale and included to further illustrate certain interior portions of the embodiment visible through a lens portion near the top of the embodiment.
